(57) **CLAIM**

The ornamental design for a lateral side extension for the midfoot of a shoe sole, as shown and described.

DESCRIPTION

FIG. 1 is a perspective view of a shoe including the lateral side extension for the midfoot of a shoe sole (hereinafter "lateral side extension");

FIG. 2 is an anterior (front) view of the shoe of FIG. 1;

FIG. 3 is a posterior (rear) view of the shoe of FIG. 1;

FIG. 4 is a lateral view of the shoe of FIG. 1;

FIG. 5 is a medial view of the shoe of FIG. 1;

FIG. 6 is a top view of the shoe of FIG. 1; and,

FIG. 7 is a bottom view of the shoe of FIG. 1.

In FIGS. 1-7 the consistent length broken lines depict unclaimed environmental structure. The broken lines and the structures they depict form no part of the claimed design. In FIGS. 1-7, the dash-dot broken lines on either side of the lateral side extension show the boundaries of these portions of the claimed design, and form no part thereof.

In FIGS. 1-7, the two types of shading indicate a contrast between the portions of the lateral side extension upon which they are found.

The embodiments of the shoe including the lateral side extension for midfoot of shoe sole shown in FIGS. 1-7 is for a right foot. The embodiments of the shoe including the lateral side extension for midfoot of shoe sole for a left foot are mirror images of the embodiments shown in FIGS. 1-7 about a sagittal plane of a human body.
